United States Patent Office

Des. 191,415
Patented Sept. 26, 1961

191,415

POWER TRANSMISSION

Harold W. Darr, Hopkins, Minn., assignor to Revo,
Inc., Minneapolis, Minn., a corporation of Minnesota

Filed Feb. 13, 1961, Ser. No. 63,905

Term of patent 14 years

(Cl. D55—1)

FIG. 1

FIG. 2

FIG. 1 is a perspective view of a power transmission showing my new design.

FIG. 2 is a perspective view showing the side and end opposite the side and end shown in FIG. 1.

I claim:

The ornamental design for a power transmission, as shown.
